UNITED STATES PATENT OFFICE.

PETER ROSSI, OF BROOKLYN, NEW YORK.

WALL COVERING.

Application filed December 3, 1927. Serial No. 237,351.

This invention relates to improvements in wall coverings, and has particular reference to a tile construction therefor.

An object of the invention is to provide an improved wall covering of simple and inexpensive construction wherein a plurality of separable tiles may be easily and quickly assembled on a wall in interlocking relation so as to simulate the ordinary tile formation such as is commonly employed in bathrooms and the like.

Another object is to form tiles, which are adapted to be placed in juxtaposition to one another, with means for securing one end of each tile in position and other means at the other end of the tile capable of being engaged by a next adjacent tile to retain said other end in close contact with the surface to which the tile is secured.

The above and other objects will appear more clearly from the following detail description, when taken in connection with the accompanying drawing, which illustrates a preferred embodiment of the inventive idea.

In the drawing—

Figure 1 is a fragmentary perspective view, partly broken away and shown in section, illustrating a wall covering constructed in accordance with the invention;

Figure 2 is a perspective view of a corner tile;

Figure 3 is a similar view of a form of tile which constitutes the major portion of the wall covering;

Figure 4 is a horizontal section illustrating the relative positions of adjacent tiles when secured in position;

Figure 5 is a vertical sectional view showing the manner in which the ends of the tiles are fixed to the wall; and

Figure 6 is a fragmentary perspective view of a molding which may be employed as a trimming.

The invention embodies as one of its essential features the provision of a plurality of tiles, each of which is stamped or otherwise formed from a sheet of material such as steel, and the outer surface of which is preferably enamelled so as to simulate the ordinary tile work that is principally used in bathrooms, kitchens, etc. With the tiles constructed as separable units the same may be readily and quickly assembled by unskilled labor to form the outer surface of a wall covering and the construction of the tiles is such that when mounted in position on a wall the same will

be securely retained in proper position. The tiles of the present invention are adapted to be mounted upon a wall of any desired construction which may include the wall board 7. 60 It is preferable, though not essential, that before securing the tiles in position the wall board be covered with a thin sheet 8 of any desired metal which is adapted to be penetrated by suitable fastening screws used to secure the tile in position and which will aid in preventing undue loosening of the fasteners after being screwed into the wall.

The tiles 9, such as shown in Figure 3, may be made in various sizes, particularly with respect to their lengths so that a wall may be completely covered. For instance, when using tiles such as shown and placing them in staggered relation upon a wall as is customary, it may become necessary to have a few 75 tiles of a length approximately one half that of the tile shown in Figure 3 so as to fill in a space between two tiles in alternate rows which extend beyond the adjacent tile in an intermediate row.

The tile 9 is formed from a suitable length of the metal used and constitutes a body portion of rectangular formation, the edges of which are provided with a peripheral flange 10 to add thickness to the tile and form abutting edges for the next adjacent tiles. At one end of each tile 9 the same has extending laterally from the opposite longitudinal edges thereof a pair of lugs 11 having openings 12 to receive the screws or other fastening devices 13 utilized to secure said end of the tile to the wall.

At the opposite end of each tile there projects longitudinally therefrom an extension 14 slightly offset from the plane of the inner edges of the flanges 10 so that the outer surface of the extension will be in substantially the same plane as said inner edges of the flanges. This enables the end of another tile 9 which carries the lugs 11 to be engaged with the extension in overlapping relation thereto and with the outer surfaces of the bodies of the two adjacent tiles flush or in the same plane. For the same purpose the lugs 11 are disposed in a manner similar to the extension 14 so that when the tiles are assembled upon the wall the entire outer surface presented thereby will be flat and none of the tiles will project outwardly beyond the outer surface of any other tile. One or more of the tiles 9 used for the wall may be provided with an opening 15 to accommodate an

electric switch or the like, and such a tile is preferably formed without the lugs 11 and extension 14, but is secured in position by means of screws 16 so as to readily enable the 5 particular tile to be easily removed in case it is desired to secure access to the switch for purposes of repair.

Corner tiles 16' are also provided and consist of the right angularly disposed sections 10 17 and 18, the latter of which is substantially one half the length of the section 17 so as to permit of carrying out the staggered relation in the various horizontal rows of tiles. The outer ends of the sections of the corner 15 tiles are each provided with lugs 19 similar to the lugs 11 and which are used to secure the corner tiles in position.

The manner in which one tile 9 overlaps the extension 14 of a next adjacent tile with 20 the outer surfaces of the two tiles in the same plane is clearly illustrated at the ends of Figure 4, while in Figure 5 it is shown how a tile in an intermediate row which is in staggered relation with respect to the tiles in the 25 two adjacent rows engages upon and overlaps the adjacent lugs 11 of the latter tiles.

After a desired area of a wall has been

covered with the tiles in the manner described, a molding 20 may be employed as a trimming 30 for the top row of tiles, for instance. This molding is bent from suitable sheet metal, preferably of the same material as used in constructing the tiles, and is formed with an inturned bottom flange 21 which rests upon the top edges of the upper row of tiles and is provided at intervals with depending extensions 22 which may be inserted between the top flanges 10 of the tiles and the sheet 8 so as to retain the molding in position. 35

What is claimed is:

A tile for walls or the like including a body 40 formed from a single sheet of metal and provided about its periphery with a lateral flange, securing lugs projecting from said flange at one end of said body, and an extension formed only at the other end of said body and projecting laterally from the free edge of said 45 flange and engageable beneath the free edge of the flange at the end of a next adjacent tile to provide the sole securing means for the end 50 of the first named tile carrying said extension.

In testimony whereof I have affixed my signature.

PETER ROSSI.
